US00D946753S

(12) **United States Design Patent** (10) Patent No.: **US D946,753 S**
(45) Date of Patent: **** Mar. 22, 2022**

(54) **BIOPSY DEVICE**

(71) Applicant: **HOLOGIC, INC.**, Marlborough, MA (US)

(72) Inventors: **Zachary Stephen Swick**, Westborough, MA (US); **David Sauvageau**, Westlake Village, CA (US); **Rosario Friedman**, Medford, MA (US); **Brett Haarala**, Framingham, MA (US)

(73) Assignee: **HOLOGIC, INC.**, Marlborough, MA (US)

(**) Term: **15 Years**

(21) Appl. No.: **29/681,944**

(22) Filed: **Feb. 28, 2019**

Related U.S. Application Data

(62) Division of application No. 29/485,001, filed on Mar. 14, 2014, now Pat. No. Des. 844,784.

CLAIM

The ornamental design for a biopsy device, as shown and described.

DESCRIPTION

FIG. 1 is a perspective view of the biopsy device;

FIG. 2 is a right side elevational view of FIG. 1;

FIG. 3 is a left side elevational view of FIG. 1;

FIG. 4 is a top plan view of FIG. 1;

FIG. 5 is a bottom plan view of FIG. 1;

FIG. 6 is a front elevational view of FIG. 1; and,

FIG. 7 is a rear elevational view of FIG. 1.

The broken lines in the drawings illustrate portions of the biopsy device and form no part of the claimed design.

1 Claim, 7 Drawing Sheets
